UNITED STATES PATENT OFFICE.

WILLIAM H. ZELTNER, OF NEW YORK, N. Y.

SORTING DEVICE.

1,278,548.

Specification of Letters Patent. Patented Sept. 10, 1918.

Application filed October 14, 1916. Serial No. 125,572.

To all whom it may concern:

Be it known that I, WILLIAM H. ZELTNER, a citizen of the United States, and resident of the borough of Manhattan, city and State of New York, have invented certain new and useful Improvements in Sorting Devices, of which the following is a specification.

The present invention relates to improvements in sorting devices, and particularly for use in the sorting of beer bottles, milk bottles or the like. At present these bottles, after being used, are brought to a clearing house in great variety, and there they are sorted and returned to their respective breweries or dairies. This has been done almost entirely by hand, the sorter after he has sorted several bottles of a particular owner, carrying these to the box intended therefor, which must necessarily be at some distance because of the number of different owners, and because of the comparatively large space required for the collected bottles of different owners. This required a great many steps, much time and the percentage of breakage was relatively high.

The present invention therefore, is intended to obviate these difficulties, and provide assorting and conveying means by which the bottles for the different owners may be safely conveyed to a place of distribution where they are placed in the proper boxes therefor by a helper. In this manner the assorter may remain seated if desired, and a great many more bottles may be assorted than was heretofore possible in a given time. It is also an object to such a device in which the bottles passing therethrough will be prevented from breaking or chipping by contact with each other.

With these and other objects in view, my invention is shown in the accompanying drawings, and will be hereinafter more fully described with reference thereto and finally pointed out in the claim.

In the accompanying drawings:

Figure 1 is an end view of my improved device,

Fig. 2 is a side view thereof,

Fig. 3 is an enlarged transverse sectional view of the chute members.

Fig. 4 is a longitudinal sectional view, and

Fig. 5 is a top view thereof.

Fig. 6 represents one end of one of the

chutes provided at the distribution end with a safety holding device.

Fig. 7 represents a transverse section of one of the rollers provided with a cushion of rubber or other material. 60

Similar reference characters indicate corresponding parts throughout the several figures of the drawings.

Referring to the drawings, and more particularly to Figs. 1 and 2 thereof, my improved conveyer and assorter, comprising a plurality of inclined shelves 10, supported between the upright ends 11 and 12, and upon the shelves are mounted a plurality of inclined chutes 13. The number of chutes 70 may be varied, and also the number of shelves, according to the requirements of the particular clearing house, each brewery or dairy whose bottles are to be assorted having one or more chutes, depending on the volume of their business. The length of the chutes is such as to reach from the place of assorting to the place of distribution. A box 14, containing the various bottles is shown at the assorting end, and a box 15 for 80 the assorted bottles is shown at the distributing end.

The chutes comprise oppositely disposed and spaced angle bars 16 and 17, forming base pieces which are secured to the shelves, 85 extending the length of the chute. Between these bars 16 and 17 there are rotatably mounted in spaced relation, a plurality of roller bearings 18, these being about an inch and a half apart. Upright side irons 19 90 and 20 are secured at each side to the bars 16 and 17, at intervals along the chute by bolts 21 which may also serve to additionally secure the chutes to the shelves, these side irons being bent in inclined direction upwardly and outwardly from the said bars, and vertically as at 22 from the said inclined portion. Strips 23 and 24, preferably of wood, are secured at each side to the side irons 19 and 20 by countersunk screws 25, 100 and serve with the roller bearings to form a channel for the bottles.

The various chutes are joined together at the portions 22 of the side irons by rivets 26, thereby forming a thoroughly rigid 105 structure which may be readily added to at any time as need demands.

The side strips hold the bottle upon the roller bearings it will be seen, preventing them from falling off at the sides. The slight 110

incline of the chutes permits the bottles to move by force of gravity, but their movement is retarded sufficiently by the roller bearings as to prevent one bottle from hitting the next with sufficient force to chip or break the same. The sorting, which requires careful examination of each bottle, proceeds at a much slower rate than the distribution so that the helper may readily take care of all of the bottles as they emerge from the chutes. The chutes are preferably provided at their distribution ends with holding means which prevent the bottles from falling. Any suitable means for this purpose may be employed. For instance, each chute may be provided at its lower end at its top with a transverse bar 30 hinged at one side of the chute and adapted when closed to engage the other side thereof.

The roller bearings in addition to retarding the movement of the bottles, also prevents any injury to the raised lettering on the bottles, which on a flat surface would become worn and chipped.

The rollers 18 may be provided with a covering 18' composed of rubber or other soft material adapted to form a cushion surface and prevent breakage of the bottles.

I have illustrated a preferred and satisfactory form of my invention, but it is obvious that changes may be made therein within the spirit and scope thereof, as defined in the appended claim.

I claim:

An assorting device for bottles comprising a stand having a series of inclined shelves disposed one above another, a series of inclined skeleton chutes disposed side by side in parallel relation on each shelf, the bottoms of said chutes having a series of spaced transverse rollers and the sides thereof comprising upwardly and outwardly inclined yieldable irons and longitudinal strips secured to said inclined irons and forming flaring troughs into which bottles of different brands respectively may be safely thrown and through which they will slide in endwise relation to individual receptacles.

In testimony that I claim the foregoing as my invention, I have signed my name in presence of two subscribing witnesses.

WILLIAM H. ZELTNER.
